END CAP FOR A VENETIAN BLIND BOTTOM BAR

Hans K. Lorentzen, Montclair, N. J., assignor to
Lorentzen Hardware Mfg. Corp., New York,
N. Y., a corporation of New York

Application July 26, 1949, Serial No. 4,142

Term of patent 14 years

(Cl. D21—6)

To all whom it may concern:

Be it known that I, Hans K. Lorentzen, a citizen of the United States, and a resident of Montclair, in the county of Essex and State of New Jersey, have invented a new, original, and ornamental Design for End Cap for a Venetian Blind Bottom Bar, of which the following is a specification, reference being had to the accompanying drawing, forming part thereof.

Figure 1 of the drawing is a perspective view of the outside end of the end cap for a venetian blind bottom bar, showing my new design.

Figure 2 is a perspective view of the inside of the same.

Figure 3 is an elevation of the inside end of the same.

Figure 4 is a section taken of the line 4—4 of Fig. 3.

The end cap is formed of transparent material.

I claim:

The ornamental design for an end cap for a Venetian blind bottom bar, substantially as shown and described.

HANS K. LORENTZEN.
